UNITED STATES PATENT OFFICE.

WILLIAM S. HOVEY, OF THREE RIVERS, MICHIGAN, ASSIGNOR TO SHEFFIELD CAR COMPANY,
OF THREE RIVERS; MICHIGAN.

RAILWAY MOTOR-CAR.

No. 914,347.

Specification of Letters Patent.

Patented March 2, 1909.

Application filed September 17, 1908. Serial No. 453,426.

To all whom it may concern:

Be it known that I, WILLIAM S. HOVEY, a citizen of the United States, residing at Three Rivers, Michigan, have invented certain new and useful Improvements in Railway Motor-Cars, of which the following is a specification.

This invention relates to improvements in railway motor cars.

10 My invention relates particularly to motor hand cars.

The main objects of this invention are: First, to provide an improved motor car which is compact and light, and, at the same time, possesses sufficient strength for the use required. Second, to provide an improved motor hand car in which the engine and its coöperating parts are so arranged and protected by the frame work and body 20 of the car that they are not likely to be injured in use, although the car is subjected to the rough usage which ordinary hand cars are subjected to. Third, to provide an improved motor hand car in which the parts 25 are so arranged as to be well balanced, thereby enabling the cars to be readily handled in lifting to and from the track.

Further objects, and objects relating to structural details will definitely appear from 30 the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which:

40 Figure 1 is a side elevation of a structure embodying the features of my invention, portions of one of the wheels and portions of the body being broken away to show the relation and arrangement of the parts. Fig. 45 2 is a vertical transverse section taken on the broken line 2—2 of Fig. 1, the wheels, axle and driving connections being shown in full lines. Fig. 3 is a detail plan view with the platform and gallows frame, and the parts 50 carried by the gallows frame, removed. Fig. 4 is a detail plan view corresponding to the view of Fig. 3 of a modified construction, the modification being in the driving connections. Fig. 5 is a sectional view taken on 55 a line corresponding to line 5—5 of Fig. 4,

the body being omitted and the wheels being indicated by dotted lines, the view showing merely details of the driving connection.

In the drawings, similar reference characters refer to similar parts throughout the 60 several views, and the sectional views are taken looking in the direction of the little arrows at the ends of the section lines.

Referring to the drawing, the body of my improved motor hand car preferably consists of the longitudinal sills 1 and the cross sills 2, the longitudinal sills and the cross sills being braced by the braces 3. Arranged on the cross sills is a platform 4. The body is also preferably provided with side rails 5 70 arranged at the edges of the platform and resting on the cross sills, as clearly appears from Figs. 2 and 3. The traction wheels 6 are provided with suitable axles 7, the bearings for the side wheels being mounted upon 75 the side bars 8. The side bars 8 are preferably secured on the under sides of the cross pieces 8' arranged under the longitudinal sills. The gallows frame 9 is preferably mounted upon the central pair of longitudinal 80 sills and projects upwardly through the platform, to which it is also secured. Details of the connections for the parts, such as bolts and the like, are not illustrated herein, as their arrangement will be obvious. 85

At its lower end, the gallows frame is preferably provided with a housing 10 which not only serves to protect the parts arranged therein, but also to brace the gallows frame.

90 Mounted on the gallows frame, is a walking beam 11, having hand-pieces 12 at each end. A driving connection is provided for the walking beam to the rear axle, which preferably consists of a crank shaft 13 which is connected to the walking beam by means 95 of the connecting rod 14. On the crank shaft is a gear 15 which meshes with the pinion 16 on the rear axle. This pinion is connected to the axle by means of a clutch, a clutch collar 17 being the means illustrated. As the 100 details of this clutch form no part of this invention, they are not shown herein. The clutch collar 17 is shifted by means of the lever 18.

105 The engine 19, which is here illustrated in conventional form, is arranged between the central pair of longitudinal sills and is suspended therefrom by means of the hangers 20, a pair of strap-like hangers being provided. The driving connections for the 110

- engine to the front axle preferably consists of a gear 21 on the front axle, and a pinion 22 on the shaft 23, which is connected to the engine shaft 24, by means of a clutch, as 25.
- 5 The details of this clutch are not here illustrated, as they form no part of this invention. This clutch is controlled by the lever 26, pivoted at 26'.
- By thus arranging the parts, the car may 10 be driven either by means of the walking beam, or by means of the engine, or both. It is, however, intended that the car shall be started by means of the walking beam, which starts the engine and then the driving connections for the walking beam to the traction wheels disconnected, or, when the car is 15 heavily loaded, both driving means may be employed. The engine is supported and located so that it does not throw the car out 20 of balance, and permits its being as easily handled as though the engine was not present. The weight is not great, as the engine is of the small size, and the driving connections for the engine and walking beam are 25 so arranged that they may be used independently or together. The engine is fully protected by the frame of the body of the car and gallows frame, and, at the same time, is readily accessible. An oil reservoir 27 is 30 preferably suspended from the gallows frame by means of the strap 28, being connected to the engine or the carburetor thereof by means of a suitable pipe 29. The radiator 30 for the engine is also preferably 35 arranged within and carried by the gallows frame. Connections therefor to the engine are not illustrated, as they form no part of this invention. The radiator is here illustrated in conventional form. By this arrangement of the parts, the delicate parts 40 are all so arranged as to be protected by the frame and body, and the hand car may be handled the same as an ordinary car without liability of disarranging the same.
- 45 I preferably provide my improved car with a brake consisting of a pair of brake shoes 31 pivoted on the side bars 8. These shoes are operated by means of the links 32, which are connected by the pivot 33 to the lower end of the foot lever 34 so that both shoes are operated by a single lever.
- In the modified construction shown in 50 Figs. 4 and 5, the engine is connected to the rear axle by means of the sprocket chain 35, the sprocket wheels 36 and 38, the shaft 39, the gear 40 and the pinion 41. The sprocket wheel 36 is arranged on the shaft 23, the sprocket wheel 38 and the pinion 41 on the shaft 39, and the gear 40 on the rear 55 axle. I prefer, however, to connect the engine to the front axle, as I have described in connection with Figs. 1, 2 and 3, as I find that the car runs more steadily on the track when so driven; that is, there is less swaying 60 movement of the car, and, further, I secure

the advantage of four driving wheels where it is necessary or desirable to use both the engine and the walking beam as driving means.

I have illustrated and described my invention in detail in the form preferred by me on account of the structural simplicity and economy thereof, although I am aware that it is capable of very great variation in structural details without departing from 70 my invention, and I desire to be understood as claiming the same specifically, as illustrated, as well as broadly.

Having described my invention, what I claim as new and wish to secure by Letters 80 Patent is:

1. In a structure of the class described, the combination with a body comprising a plurality of longitudinal sills and a platform; a centrally arranged gallows frame secured 85 to the central pair of sills and arranged through said platform; traction wheels; axles therefor; a walking beam; driving connections therefor to the rear axle, comprising a crank shaft carried by the said central 90 pair of sills, a connecting rod for said crank shaft to said walking beam, a gear on said crank shaft, a pinion on the rear axle arranged to mesh with the gear on said crank shaft, and a clutch connection for said 95 pinion to said axle; an engine carried by and arranged between the said central pair of sills and under the said gallows frame; driving connections for said engine to the forward axle, comprising a pinion, a clutch 100 connection therefor to the engine shaft, and a gear on the forward axle arranged to mesh with said pinion; an oil storage tank arranged within and carried by said gallows frame; and a radiator arranged within and 105 carried by said gallows frame.

2. In a structure of the class described, the combination with a body comprising a plurality of longitudinal sills and a platform; a centrally arranged gallows frame secured 110 to the central pair of sills and arranged through said platform; traction wheels; axles therefor; a walking beam; driving connections therefor to the rear axle, comprising a crank shaft carried by the said central 115 pair of sills, a connecting rod for said crank shaft to said walking beam, a gear on said crank shaft, a pinion on the rear axle arranged to mesh with the gear on said crank shaft, and a clutch connection for said 120 pinion to said axle; an engine carried by and arranged between the said central pair of sills and under the said gallows frame; driving connections for said engine to the forward axle, comprising a pinion, a clutch connection 125 therefor to the engine shaft, and a gear on the forward axle arranged to mesh with said pinion; and an oil storage tank arranged within and carried by said gallows frame.

3. In a structure of the class described, the combination with a body comprising a plurality of longitudinal sills and a platform; a centrally arranged gallows frame secured to the central pair of sills and arranged through said platform; traction wheels; axles therefor; a walking beam; driving connections therefor to the rear axle, comprising a crank shaft carried by the said 10 central pair of sills, a connecting rod for said crank shaft to said walking beam, a gear on said crank shaft, a pinion on the rear axle arranged to mesh with the gear on said crank shaft, and a clutch connection 15 for said pinion to said axle; an engine carried by and arranged between the said central pair of sills and under the said gallows frame; driving connections for said engine to the forward axle, comprising a pinion, a 20 clutch connection therefor to the engine shaft, and a gear on the forward axle arranged to mesh with said pinion; and a radiator arranged within and carried by 25 said gallows frame.

4. In a structure of the class described, the combination with a body comprising a plurality of longitudinal sills and a platform; a centrally arranged gallows frame secured to the central pair of sills and arranged 30 through said platform; traction wheels; axles therefor; a walking beam; driving connections therefor to the rear axle, comprising a crank shaft carried by the said central pair of sills, a connecting rod for 35 said crank shaft, to said walking beam, a gear on said crank shaft, a pinion on the rear axle arranged to mesh with the gear on said crank shaft, and a clutch connection for said pinion to said axle; an engine carried by and arranged between the said central 40 pair of sills and under the said gallows frame; driving connections for said engine to the forward axle, comprising a pinion, a clutch connection therefor to the engine 45 shaft, and a gear on the forward axle arranged to mesh with said pinion.

5. In a structure of the class described, the combination with a car body; gallows frame; traction wheels; axles therefor; a walking 50 beam; driving connections therefor to the rear axle, comprising a crank shaft, a connecting rod for said crank shaft to said walking beam, a gear on said crank shaft, a pinion on the rear axle arranged to mesh 55 with the gear on said crank shaft, and a clutch connection for said pinion to said axle; an engine; driving connections for said engine to the forward axle, comprising a pinion, a clutch connection therefor to the 60 engine shaft, and a gear on the forward axle arranged to mesh with said pinion; an oil storage tank arranged within and carried by said gallows frame; and a radiator arranged within and carried by said gallows 65 frame.

3. In a structure of the class described, the combination with a car body; gallows frame; traction wheels; axles therefor; a walking beam; driving connections therefor to the rear axle, comprising a crank shaft, a connecting rod for said crank shaft to said walking beam, a gear on said crank shaft, a pinion on the rear axle arranged to mesh 70 with the gear on said crank shaft, and a clutch connection for said pinion to said axle; an engine; driving connections for said engine to the forward axle, comprising a pinion, a clutch connection therefor to the engine shaft, and a gear on the forward axle arranged to mesh with said pinion; and an 75 oil storage tank arranged within and carried by said gallows frame.

7. In a structure of the class described, the combination with a car body; gallows frame; traction wheels; axles therefor; a walking beam; driving connections therefor to the rear axle, comprising a crank shaft, a connecting rod for said crank shaft to said walking beam, a gear on said crank shaft, a pinion on the rear axle arranged 80 to mesh with the gear on the said crank shaft, and a clutch connection for said pinion to said axle; an engine; driving connections for said engine to the forward axle, comprising a pinion, a clutch connection therefor to the 85 engine shaft, and a gear on the forward axle arranged to mesh with said pinion; and a radiator arranged with and carried by said gallows frame.

8. In a structure of the class described, the combination with a car body; gallows frame; traction wheels; axles therefor; a walking beam; driving connections therefor to the rear axle, comprising a crank shaft, a connecting rod for said crank shaft to 90 said walking beam, a gear on said crank shaft, a pinion on the rear axle arranged to mesh with the gear on the said crank shaft, and a clutch connection for said pinion to said axle; an engine; driving connections for said engine to the forward axle, comprising a pinion, a clutch connection therefor to 95 the engine shaft, and a gear on the forward axle arranged to mesh with said pinion; and a radiator arranged with and carried by said gallows frame.

8. In a structure of the class described, the combination with a car body; gallows frame; traction wheels; axles therefor; a walking beam; driving connections therefor to the rear axle, comprising a crank shaft, a connecting rod for said crank shaft to 100 said walking beam, a gear on said crank shaft, a pinion on the rear axle arranged to mesh with the gear on the said crank shaft, and a clutch connection for said pinion to said axle; an engine; and driving 105 connections for said engine to the forward axle, comprising a pinion, a clutch connection therefor to the engine shaft, and a gear on the forward axle arranged to mesh with said pinion.

9. In a structure of the class described, the combination with a car body; gallows frame; traction wheels; axles therefor; a walking beam; driving connections therefor to the rear axle, comprising a crank shaft, a connecting rod for said crank shaft to 110 said walking beam, a gear on said crank shaft, a pinion on the rear axle arranged to mesh with the gear on said crank shaft, and a clutch connection for said pinion to said axle; an engine; and driving 115 connections for said engine to the forward axle, comprising a pinion, a clutch connection therefor to the engine shaft, and a gear on the forward axle arranged to mesh with said pinion.

9. In a structure of the class described, the combination with a car body; gallows frame; traction wheels; axles therefor; a walking beam; driving connections therefor to the rear axle, comprising a crank shaft, a connecting rod for said crank shaft to 120 said walking beam, a gear on said crank shaft, a pinion on the rear axle arranged to mesh with the gear on said crank shaft, and a clutch connection for said pinion to said axle; an engine arranged under the said gallows frame; and driving connections for said engine to the forward axle, comprising a pinion, a clutch connection therefor to the engine shaft, and a gear on the 125 engine shaft.

forward axle arranged to mesh with said pinion.

10. In a structure of the class described, combination with a body, comprising a plurality of longitudinal sills and a platform; a centrally arranged gallows frame, secured to the central pair of said sills, and arranged through said platform; traction wheels; a walking beam; driving connections therefor to the traction wheels; means for disconnecting said driving connections; an engine carried by and arranged between the said central pair of sills and under said gallows frame; driving connections for said engine to the traction wheels, means for disconnecting said driving connections; an oil storage tank arranged within and carried by said gallows frame; and a radiator arranged within and carried by said gallows frame.

11. In a structure of the class described, combination with a body, comprising a plurality of longitudinal sills and a platform; a centrally arranged gallows frame, secured to the central pair of said sills, and arranged through said platform; traction wheels; a walking beam; driving connections therefor to the traction wheels; means for disconnecting said driving connections; an engine carried by and arranged between the said central pair of sills and under said gallows frame; driving connections for said engine to the traction wheels, means for disconnecting said driving connections; and an oil storage tank arranged within and carried by said gallows frame.

12. In a structure of the class described, combination with a body, comprising a plurality of longitudinal sills and a platform; a centrally arranged gallows frame, secured to the central pair of said sills, and arranged through said platform; traction wheels; a walking beam; driving connections therefor to the traction wheels; means for disconnecting said driving connections; an engine carried by and arranged between the said central pair of sills and under said gallows frame; driving connections for said engine to the traction wheels, means for disconnecting said driving connections; and a radiator within and carried by said gallows frame.

13. In a structure of the class described, combination with a body, comprising a plurality of longitudinal sills and a platform; a centrally arranged gallows frame, secured to the central pair of said sills, and arranged through said platform; traction wheels; a walking beam; driving connections therefor to the traction wheels; means for disconnecting said driving connections; an engine carried by and arranged between the said central pair of sills and under said gallows frame; driving connections for said

engine to the traction wheels, and means for disconnecting said driving connections.

14. In a structure of the class described, combination with a car body, a gallows frame; traction wheels; a walking beam; an engine arranged under said gallows frame; driving connections for said engine and walking beam to the traction wheels; means for connecting and disconnecting said driving connections; an oil storage tank arranged within and carried by said gallows frame; and a radiator arranged within and carried by said gallows frame.

15. In a structure of the class described, combination with a car body, a gallows frame; traction wheels; a walking beam; an engine arranged under said gallows frame; driving connections for said engine and walking beam to the traction wheels; means for connecting and disconnecting said driving connections; and an oil storage tank arranged within and carried by said gallows frame.

16. In a structure of the class described, combination with a car body, a gallows frame; traction wheels; a walking beam; an engine arranged under said gallows frame; driving connections for said engine and walking beam to the traction wheels; means for connecting and disconnecting said driving connections; and a radiator arranged within and carried by said gallows frame.

17. In a structure of the class described, the combination with a car body, of a gallows frame; traction wheels; a walking beam; an engine arranged under said gallows frame; driving connections for said engine and walking beam to the traction wheels; and means for connecting and disconnecting said driving connections.

18. In a structure of the class described, the combination with a car body, of a gallows frame; traction wheels; a walking beam; an engine; driving connections for said engine and walking beam to the traction wheels; means for disconnecting and connecting said driving connections; an oil storage tank arranged within and carried by said gallows frame; and a radiator arranged within and carried by said gallows frame.

19. In a structure of the class described, the combination with a car body, of a gallows frame; traction wheels; a walking beam; an engine; driving connections for said engine and walking beam to the traction wheels; means for connecting and disconnecting said driving connections; and an oil storage tank arranged within and carried by said gallows frame.

20. In a structure of the class described, the combination with a car body, of a gallows frame; traction wheels; a walking beam; an engine; driving connections for said engine and walking beam to the trac-

- tion wheels; means for connecting and disconnecting said driving connections; and a radiator arranged within and carried by said gallows frame.
21. In a structure of the class described, 5 the combination with a car body, of a gallows frame; traction wheels; a walking beam; an engine; driving connections for said engine and walking beam to the traction wheels; and means for connecting and disconnecting said driving connections.
22. In a structure of the class described, 10 the combination with a car body, of a gallows frame; traction wheels; a walking beam; an engine arranged under said gallows frame; driving connections for said engine and walking beam to the traction wheels; an oil storage tank arranged within and carried by said gallows frame; and a 15 radiator arranged within and carried by said gallows frame.
23. In a structure of the class described, 20 the combination with a car body, of a gallows frame; traction wheels; a walking beam; an engine arranged under said gallows frame; driving connections for said engine and walking beam to the traction wheels; and an oil storage tank arranged within and carried by said gallows frame.
24. In a structure of the class described, 30 the combination with a car body, of a gallows frame; traction wheels; a walking beam; an engine arranged under said gallows frame; driving connections for said engine and walking beam to the traction 35 wheels; and a radiator arranged within and carried by said gallows frame.
25. In a structure of the class described, 40 the combination with a car body, of a gallows frame; traction wheels; a walking beam; an engine arranged under said gallows frame; and driving connections for said engine and walking beam to the traction 45 wheels.
26. In a structure of the class described, 50 the combination with a car body, of a gallows frame; traction wheels; a walking beam; an engine; and driving connections for said engine and walking beam to the traction wheels.

In witness whereof, I have hereunto set my hand and seal in the presence of two witnesses.

WILLIAM S. HOVEY. [I. S.]
